FIG. 1.

FIG. 2.

INVENTOR

Harold Roth

BY *John Price*

ATTORNEY

UNITED STATES PATENT OFFICE

162,086

BRASSIÈRE SLIP

Harold Roth, New York, N. Y.

Application June 2, 1948, Serial No. 146,721

Term of patent 14 years

(CL. D3—26)

To all whom it may concern:

Be it known that I, Harold Roth, a citizen of the United States, and residing at New York city, county and State of New York, have invented a new, original, and ornamental Design for a Brassière Slip, of which the following is a specification, reference being had to the accompanying drawings, forming part hereof and in which:

Fig. 1 is a front perspective view of a brassière slip embodying the design of the present invention.

Fig. 2 is a rear perspective view.

I claim:

The ornamental design for a brassière slip, substantially as shown.

HAROLD ROTH,
